UNITED STATES PATENT OFFICE

ARTHUR C. McWILLIAMS, OF CHICAGO, ILLINOIS.

ELECTRIC-LAMP FIXTURE.

1,145,383.

Specification of Letters Patent. Patented July 6, 1915.

Application filed April 20, 1912. Serial No. 692,076.

To all whom it may concern:

Be it known that I, ARTHUR C. McWILLIAMS, a citizen of the United States, residing at Chicago, in the county of Cook and State of Illinois, have invented a certain new and useful Improvement in Electric-Lamp Fixtures, of which the following is a specification:

My invention relates to electric lamp fixtures and the object of the invention is to provide a simply constructed fixture capable of being adjusted in various ways to suit conditions of use. Among other adjustments may be noted the vertical adjustment of the lamp socket with reference to the shade holder and shade to accommodate lamps of various sizes, and shades of various forms and for various situations; also the adjustment of the shade holder with reference to the stem of the fixture and also the adjustment of the canopy with reference to the ceiling or wall upon which the fixture is to be attached.

Another object of the invention is to provide a fixture so constructed that it may be readily taken down for refinishing, inspection or repair and be readily replaced with a minimum of time and trouble.

Contributing to these general objects it is my purpose to provide certain advantageous details of construction which will be hereinafter more particularly described and claimed.

I accomplish my objects by the mechanism illustrated in the accompanying drawings in which—

Figure 1 is an axial section. Fig. 2 is an elevation of some of the internal parts of the mechanism. Fig. 3 is a transverse section taken on line 3—3 Fig. 1. Fig. 4 is an axial section showing one of the connector bars and associated parts inclosed in the stem. Fig. 5 is a transverse section taken on the line 5—5 Fig. 1. Figs. 6 and 7 are perspective views of the connector bars. Fig. 8 is a perspective view of the clip employed on the connector bars, and Fig. 9 is a perspective of the clamping ring which supports the shade holder.

Similar reference characters denote like parts in the different views.

As the fixture is ordinarily attached to the ceiling the parts will be described as if the fixture were in this position and the chief component parts arranged in vertical posi-

tion. It will be understood, however, that the fixture is equally operative when attached to a wall.

In the present form, selected to illustrate the invention, the stem is formed in two parts, the terminal 1, formed of metal and internally threaded to screw upon the stationary fixture stub 2, and the stem proper 3, consisting of any suitable insulating material which is preferably dove-tail molded to the terminal 1. The lower portion of stem 3 is cylindrically chambered, axially, and thus makes a sliding fit with the lamp socket 4. In the preferred construction, said socket is provided with an internal metallic bushing 5, which is threaded to receive the stem of the lamp 6. A terminal piece 10 is mounted in socket 4 in position to contact the central terminal of the lamp, said terminal piece being connected by a screw 11 or otherwise to the lower connector bar 12. The metallic bushing is electrically connected by the screw 15 or otherwise to the lower connector bar 16 of opposite polarity to bar 12. Said connector bars make sliding connection with the upper connector bars 18, these bars being shown in perspective in Figs. 6 and 7. As the lower bars 12 and 16 are rigidly connected to the lamp socket 4, they will contribute to the support of the latter and will move in unison with it. In order to avoid any danger of slipping by reason of the weight or vibration of the parts, it is desirable to roughen the contacting faces of the connector bars as best shown in Fig. 6.

The upper bars 18 are screwed or otherwise fastened to the upper end of stem 3 and are provided with conductive terminals 19 whereby they may be electrically connected to the supply conductors 20.

Means are provided for regulating the pressure between the contacting surfaces of the connector bars above mentioned, for regulating the friction between them. The means for thus regulating the friction are shown in Figs. 1, 8 and elsewhere, and include a clip 25 which is U shaped and provided with a slot 26 at the bend in the bottom for receiving a pair of the connector bars. At the upper end, the lower connector bars have a spring bend 27, having an aperture 28 adapted to receive tension screws 29, the latter being shown especially in Figs. 1, 3, 4 and 5. These screws pass through 105

apertures 30 and 31 in the clip, the aperture 30 being loose enough to loosely receive the screw while the aperture 31 is threaded to coat with the screw. The upper bars 18 have a longitudinal slot 33 through which the tension screws pass. The result is two fold, first the amount of friction between the sliding connector bars may be regulated, second the clip, as it supports the two ends 10 of the tension screw always holds it horizontal, thereby causing it to travel freely in slot 33.

From the foregoing it will be seen that the lamp socket and lamp are vertically adjustable in the stem and that the lamp will be provided with current when the parts are at any elevation within the range of adjustment.

I will now describe the manner of supporting the canopy and shade holder and adjusting them to the positions required.

A clamping collar 37 shown in perspective in Fig. 9 encircles the stem 3 and has a slot 38 in its side for rendering the upper edge 25 of the collar contractile. At the upper edge said collar is provided with two ears 39 one of which is screw threaded to take a clamping screw 40 as best shown in Fig. 3. The other ear is apertured to loosely receive the screw; consequently the collar may 30 be clamped at any desired elevation upon stem 3 below the feed wires 20 and above the annular shoulder 43 formed in the stem as best shown in Fig. 1. This shoulder is 35 not an essential feature of the construction but is desirable as it forms a stop for limiting the downward movement of the collar 37. Said collar has a vertical slot 45 for receiving the latch 46 shown in detail in 40 Figs. 2 and 5. Latch 46, when in acting position, has its major portion lying within a chamber 47 formed within stem 3 but projects through slot 45 above mentioned and through a corresponding slot 48 formed near 45 the upper end of the cylindrical portion of the shade holder 50. Slot 48 is curved as best shown in Fig. 2 and receives a pin 51 secured to and projecting from the side of ring 37. The result is that the ring and 50 shade holder are connected by what is termed a "bayonet joint". When the latch is drawn down far enough to lie within both of the slots 45 and 48 in the collar and shade holder respectively, relative rotation of the 55 collar and shade holder will be prevented and, on account of the presence of the bayonet joint will prevent the collar and shade holder from being disconnected. When however, the latch is raised by screw 55 high 60 enough to leave slot 48, said collar and shade holder may be disconnected. This interrelation will be obvious upon reference to Fig. 2. Screw 55 by which the vertical position of latch 46 is controlled is preferably 65 housed within stem 3 and projects down to

the bottom of the latter where the screw head 56 is accessible from the lower end of the fixture when the shade 58 is not present. As the open end of slot 48 is at the top, gravity tends to cause the latch to enter and 70 remain in it, and hence the latch may safely be operated by merely pushing the screw up or down to cause the latch to enter or leave said slot.

The latch and associated parts are normally inclosed by the canopy 60. The shade holder may assume any suitable form at the lower end adequate for supporting the shade. An annular bead 62 is formed at a convenient point near the upper end of the 80 shade holder, and upon this bead rests the lower extremity of the canopy. The elevation of the canopy therefore depends upon the elevation of the shade holder, and the elevation of the shade holder depends upon 85 the vertically adjustable collar 37. It will be understood by those who have had practical experience that the exposed surface of the ceiling will vary with respect to the elevation of the fixture stub 2; but as the canopy and shade-holder are vertically adjustable by reason of the vertical adjustability of the clamping collar 37, a considerable range of variation in the ceiling is easily compensated for.

In operation when it is desired to disassemble the parts all that is necessary is to lift the latch 46 out of slot 48, whereupon by slightly rotating the shade holder, the latter may be disconnected from collar 37 90 and the shade, shade holder and canopy may be simultaneously lowered, and removed. The wiring connections are then 95 fully exposed and by disconnecting the end of the feed wires from the terminals 19, the 100 entire remaining portion of the fixture may be removed by merely unscrewing the terminal 1 from the stub 2. The extreme ease with which the shade holder and canopy 105 may be lowered or replaced is of great practical advantage, for it is frequently desirable to inspect the wire connections for various reasons. Furthermore, fixtures are apt to tarnish and require replating or refinishing and with the ordinary fixtures this is 110 not possible without requiring considerable labor and trouble on the part of an electrician. With my construction also, it is possible, by carrying in stock a few patterns 115 of shade holders and a few patterns of canopies to produce a great variety of combinations of the two, thus with little expense 120 avoiding the monotony of identical fixtures throughout the building.

As the parts 1 and 2 virtually constitute 125 a single piece, it will be seen that the bulk of the fixture is comprised of but three main parts in addition to the lamp socket, to wit: the canopy, shade holder and stem.

In adjusting the lamp socket vertically to 130

bring the different sizes of lamps to the proper position relatively to the shade, it is merely necessary to grasp the socket or even the lamp itself and push it up or down to 5 the elevation required. On account of the formation of the connector bars, the socket and lamp will securely maintain any elevation to which they are brought. If the buildings in which the fixtures are mounted 10 are subject to great vibrations as in a factory, the friction between the connectors may be increased to any desired extent by adjusting the tension screws 29. Conversely for ordinary office buildings, this friction 15 may with safety be reduced to a minimum thus rendering the lamp vertically adjustable with the expenditure of little energy on the part of the user.

Having thus described my invention, what 20 I claim as new, and desire to secure by Letters Patent, is:

1. In a lamp fixture, the combination of a stem, a lamp socket slidable therein, a pair of connector bars connected to the terminals 25 of the socket, a second pair of connector bars secured to the stem and adapted to make sliding contact with the first mentioned pair, and means for controllably varying the amount of friction between said 30 connector bars.

2. In a lamp fixture, the combination of a stem, a lamp socket slidable therein, a pair of connector bars connected to the terminal 35 of the socket, a second pair of connector bars secured to the stem and adapted to make sliding contact with the first mentioned pair, and a clip apertured for the reception of two coöperating connector bars, said clip being adapted to regulate the friction 40 between the connector bars.

3. In a lamp fixture, the combination of a stem, a lamp socket slidable therein, a pair of connector bars connected to the terminal of the socket, a second pair of connector bars 45 secured to the stem and adapted to make sliding contact with the first mentioned pair, one pair of said bars being longitudinally slotted, a clip on each two coöperating bars apertured for the reception thereof and a 50 tension screw mounted in said clips and passing through the slots aforesaid and also passing through apertures in the connector bars which coöperate with the ones which are slotted.

55 4. In a lamp fixture, the combination of a stationary stem, having a longitudinal center bore for a considerable portion of its length, a lamp socket slidable in said center bore, a pair of connector bars connected to 60 the terminal of the socket, a second pair of connector bars fastened to the stationary stem and adapted to make sliding contact with the first mentioned pair, said connector bars being located chiefly within the bore 65 of the stem and the stationary bars having

their upper ends accessible from the sides of the stem to facilitate connection with feed wires and means for maintaining the co-operating connector bars in sliding contact with each other.

5. In a lamp fixture, the combination of a stationary stem, a collar mounted thereon, a shade holder encircling said collar and connected thereto by a bayonet joint, said collar and shade holder having slots adapted 70 to register with each other, and a latch adapted to penetrate said slots to prevent relative rotation of the collar and shade holder to thereby prevent the disconnecting of the bayonet joint.

6. In a lamp fixture, the combination of a stationary stem, a collar mounted thereon, a shade holder encircling said collar and connected thereto by a bayonet joint and a latch 75 slidingly engaging said collar, said latch being vertically movable and laterally non-movable, there being an open ended slot in said shade holder adapted to receive said latch to prevent the shade holder from rotating and being thereby disconnected from 80 the collar.

7. In a lamp fixture, the combination of a stationary stem, a shade holder encircling the same, and means for attaching and detaching said shade holder from said stem, 85 said attaching and detaching means comprising a latch housed for the most part in said stem and vertically movable therein, and means for vertically moving said latch, said holder having an open end slot which 90 the latch may enter and leave.

8. In a lamp fixture, the combination of a stationary stem of insulating material, a shade holder encircling said stem and vertically slidable thereon, a canopy supported 105 upon said shade holder, and a lamp socket within the stem, said socket being vertically adjustable independently of the shade holder.

9. In a lamp fixture, the combination of a stationary stem of insulating material substantially cylindrical on the outside and having a center bore extending the major portion of its length, commencing at the bottom, a lamp socket within the center bore of 110 the stem and vertically adjustable with reference thereto, terminals secured to said stem for connection to electric feed wires, adjustable connectors for maintaining electrical connection between the lamp socket 115 and the terminals on the stem and a shade holder and a canopy both encircling said stem and forming a housing for the above mentioned parts.

10. In a lamp fixture, the combination of 120 a stationary stem of insulating material substantially cylindrical on the outside and having a center bore extending the major portion of its length, commencing at the bottom, a vertically adjustable lamp socket 125

within the center bore of the stem, a pair of connector bars connected to the socket terminals, another pair of connector bars fastened to said stem, means for maintaining the electrical connection between the pairs of connector bars when the lamp socket is vertically adjustable, a shade holder encircling and fitting said stem, said shade holder being vertically adjustable independently of the lamp socket, and a canopy encircling said stem and resting lightly upon the same to be supported thereby.

In witness whereof, I have hereunto subscribed my name in the presence of two witnesses.

ARTHUR C. McWILLIAMS.
